UNITED STATES PATENT OFFICE

106,302

DESIGN FOR A DRESS ENSEMBLE

Rose La Giusa, New York, N. Y.

Application August 10, 1937, Serial No. 70,957

Term of patent 3½ years

To all whom it may concern:

Be it known that I, Rose La Giusa, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view of the dress member of the ensemble.

Fig. 3 is a front view of the dress member of the ensemble.

The rear view of the jacket portion of the ensemble is conventional.

I claim:

The ornamental design for a dress ensemble substantially as shown and described.

ROSE LA GIUSA.
